UNITED STATES PATENT OFFICE.

WILLIAM E. WINE, OF TOLEDO, OHIO.

CAR-DOOR-LOCKING DEVICE.

Application filed January 12, 1922. Serial No. 528,652.

To all whom it may concern:

Be it known that I, WILLIAM E. WINE, a citizen of the United States of America, residing at Toledo, in the county of Lucas and 5 State of Ohio, have invented certain new and useful Improvements in Car-Door-Locking Devices, of which the following is a specification.

My invention relates to new and useful improvements in car door locking devices and 10 has for an object to provide a device that will tightly hold the doors in their closed position and lock the same against accidental opening. 15 Another object of the present invention is to provide a locking device consisting preferably of a bracket in which is pivotally mounted a hook that is designed to engage a ledge secured to the bottom of the door, 20 and to provide means consisting of a partly removable member having an enlarged portion or head on its inner end that will tightly fit between the hook and a casing on the housing, and thereby prevent the accidental 25 disengagement of the hook from the ledge of the door.

Still another object of the present invention is to provide a locking device that is extremely efficient in action, consisting of 30 but two moving parts, one the hook, which is pivotally mounted on the bracket and the other the wedge member that is contained in a casing on the bracket, and although freely movable therein cannot be lost from 35 the casing.

With these and other objects in view, the invention consists in certain new and novel constructions and combination of parts as will be hereinafter more fully described 40 and pointed out in the claims.

Referring now to the drawings, showing a preferred embodiment of the invention

Fig. 1 is a view in side elevation showing a fragmentary portion of a car, one side of 45 a door, and the locking device supporting and locking the door in its closed position, a portion of the casing being removed for sake of clearness.

Fig. 2 is a sectional view taken on line 50 2-2 of Fig. 1 looking in the direction of the arrows.

Referring now more in detail to the drawings, a fragmentary portion 1, of the side of a car is shown having a bracket 2 secured 55 to the center sill (not shown) from which is hinged the door 3, that has secured to

the bottom thereof the angle iron 4, that extends completely across the door and out beyond its free edges on both sides to form ledges that are to be engaged by hooks 5 60 mounted on the brackets 6, which brackets are secured to the side of the car body.

It will be understood that I have only shown one bracket and hook in the drawings, but in most instances a similar locking arrangement is used on the other side of the door also, and a description of one will be a description of both.

The bracket 6 may be rectangular in shape and may be provided with the bosses 70 7 through which rivets 8 will be passed to secure the bracket to the side of the car, while a plate 9 may be used on the inner side of the car opposite the lower bosses to provide a reinforcement for the locking devices, 75 if desired.

Preferably formed integrally with the bracket 6 is the casing 10, which as will be seen, extends as at 11, above the upper edge of the bracket, and is provided with the slot 80 12, through which extends the outer end of a wedge member 13, shortly to be described. An arcuate rib 14 is formed on the bracket at the topmost point of the casing 10 to restrict the opening of the slot 12. The width 85 of the casing 10 is approximately twice the width of the shank of the hook 5 so that the hook may be free to swing rearwardly from disengagement with the ledge formed by the angle iron. Also formed at the bottom of 90 this casing is a slot or opening between the bracket and the wall of the casing so that the hook may move rearwardly, and similarly, there is a rib 15 that restricts this lower slot. 95

Referring now to the wedge member 13 it will be seen that it consists of a shank or body portion 16 and the enlarged head 17, the diameter of the head being such that when it is lowered, as may be seen in Fig. 1, 100 it will be jammed between the rear edge of the hook and the rear wall of the casing 10, thereby holding the hook in its forward and locked position with relation to the door. The rib 15 in the lower slot or opening prevents the wedge member 13 from dropping without the casing while the arcuate rib 14, at the top of the casing, prevents the accidental removal of the wedge-shaped member from without the top of the casing. 105

The wedge member 13 is enterable within the casing from the bottom when the hook

5 is not in place. After the hook has been connected in place the length of the slot at the bottom of the casing is so reduced by the presence of the hook that the wedge member 13 cannot be removed.

10 The outer end of the wedge-shaped member 13 is provided with a lug 18 which forms a short handle or gripping member so that when desired to remove the wedge-shaped member 13 from its locking position, the same may be grasped and the wedge-shaped member pulled upwardly and then outwardly until it assumes the position shown clearly in the dotted lines in Fig. 1.

15 In the present embodiment of the invention, I have shown a bolt 19 as passing through the casing 10 and the bracket 6 and the upper end of the hook 5, which bolt also extends through the side of the car body and 20 is secured by the nut 20, while the opening in the casing and the bracket is shown provided with the bosses 21.

25 It is to be understood, however, that other forms of pivotal support might be used rather than a bolt or nut, if desired.

Also, I have shown a rib 22 shown between the casing 10 and the bracket 6, and a small projecting lug 23, which is a continuation of the rear wall of the casing, both 30 of which add strength to the device, and in a like manner further reinforcing or strengthening ribs may be used if found desirable or necessary.

35 The operation of the locking device is exceedingly simple.

Presuming the door is in its open position, the wedge-shaped member 13 will be resting on the lower edge of the upper slot 12 while the enlarged head 17 will impinge against 40 the arcuate rib 14. The door will then be raised so that the hook 5 will engage the angle iron 4 which will support and hold the door in its closed position after which the wedge-shaped member will be forced inwardly and downwardly so that the enlarged head 17 will jam between the rear edge of the hook and the rear wall of the casing 10, and thus tightly hold the hook in its forward and locked position.

50 From the foregoing it will be seen that the locking device consists of but two moving parts, easily operated, and will tightly hold the door in its locked position until the handle of the wedge-shaped member 13 is 55 grasped to withdraw the wedge-shaped member from its locking position within the casing.

Furthermore, the locking device is one that is relatively cheap to manufacture, efficient in service and relatively light and compact in nature.

Having thus described my invention, what I claim as new and desire to secure by Letters Patent is:

65 1. A locking device for drop doors com-

prising a bracket, a hook pivotally mounted on said bracket and adapted to engage a ledge of a door to support the same, a casing formed on said bracket partly enclosing said hook, and means carried within said casing for holding said hook in its forward and locked position, said hook-holding means being removable from the casing only upon removal of the said hook. 70

2. A locking device for drop doors comprising a bracket, a casing on said bracket and a hook pivotally mounted on said bracket and partly within said casing, said casing open at its lower edge to permit the swinging of said hook, a locking means for 80 said hook, carried within said casing and forming a wedge between the rear of said hook and the rear wall of said casing when in its locked position to thereby hold the hook in its operative position in said casing. 85

3. A locking device for drop doors comprising a bracket, a casing formed on said bracket and a hook pivotally mounted in said casing, said casing being open along its lower edge to permit the swinging movement of said hook, a loosely carried member in said casing having an enlarged head, said head abutting against the rear edge of said hook and the rear edge of said casing when in its operative position to thereby 95 hold the hook in its locked position, and said member with the enlarged head adapted to be lifted upwardly to thereby unlock said hook.

4. A locking device for drop bottom doors 100 comprising a bracket, a casing formed on said bracket, a hook pivotally mounted within said casing, the said casing being open at its lower edge to permit the swinging of said hook, the upper portion of said casing provided with a slot, a member loosely carried in said casing, the upper end of which at all times extends through said slot, said member engaging the rear inner wall of said casing and the rear edge of said hook 110 when in its operative position to lock said hook, and said member being adapted to be raised out of engagement with the hook and the said rear wall of said casing to permit the hook to swing to an unlocked position. 115

5. In a locking device for drop bottom doors, a bracket having a base portion with a casing formed thereon, said casing extending above the upper edge of the base portion of said bracket, said casing being provided with a slot in its upper portion and a rib for restricting a portion of said slot, said casing being open along its entire lower edge, a hook pivotally mounted in said casing, a member carried in said casing comprising a shank and an enlarged head, the said head engaging the rear wall of said casing and the rear edge of said hook, to lock the said hook when the said member is in its locking position, and said mem- 125 ber is in its locking position, and said mem- 130

ber having the outer end of its shank extending through the slot in the top of the casing at all times, said member being adapted to be retracted to permit the hook to swing rearwardly in said casing and the rib in the upper slot preventing the accidental removal of said member from said casing.

6. A locking device for drop bottom doors, comprising a bracket, a hook mounted on said bracket and adapted to engage a ledge of a door and thereby support the same, a casing partly enclosing said hook and open at its lower edge to allow the swinging of said hook, the said casing extending above the pivotal point of said hook and provided with a slot near its upper end, an arcuate rib formed at the upper end of said slot, a member loosely carried in said casing and having an enlarged head, the shank of said member always extending through said slot, the enlarged head abutting the rear edge of said hook and the rear wall of said casing when said member is in its locking position to hold the hook against movement, a rib formed along the lower edge of said casing to prevent the member from dropping without the said casing, said member adapted to be lifted upwardly and the outer end swung downwardly to permit the hook to swing to an unlocked position, the arcuate rib in the top of the casing engaging the head of said member to hold the same in its unlocked position and to prevent the acci-

dental disengagement of the member from the casing.

7. In combination with a freight car having a drop bottom door, a ledge formed on said door, a bracket mounted above said ledge, a casing formed on said bracket, a hook pivotally mounted in said casing and engaging said ledge to support said door when the hook is in its forward position, a member carried within said casing having an enlarged head engaging the rear of said hook and the rear inner wall of said casing when said member is in its lowered and locked position, the upper end of said casing provided with a slot and the upper end of said member extending through said slot, an arcuate rib formed at the top of said casing, the lower edge of said casing being opened to allow the swinging movement of said hook, and a rib at the lower edge of said casing to limit the downward movement of said member, the said member carried in said casing adapted to be raised and swung parallel with the door to permit the hook to be disengaged from the ledge to unlock the door, and the lower edge of said slot and the arcuate rib in the top of the casing preventing the accidental removal of said member from said casing.

In testimony whereof I affix my signature.

WILLIAM E. WINE.
